SACK HOLDER

Filed Oct. 17, 1929

UNITED STATES PATENT OFFICE

WILLIAM S. TOPPER, OF BUCYRUS, OHIO

SACK HOLDER

Application filed October 17, 1929. Serial No. 400,385.

The object of the invention is to provide a sack holder comprising complemental arms adapted for disposition in and distending the mouth of a sack, the arms being readily shiftable to reverse their relative positions, so that the device is quickly adaptable for use with either of two sizes of sacks; to provide a device of this kind which is readily adjustable as to height; and to provide a construction which is of simple form and therefore susceptible of cheap manufacture and low marketing cost.

With this object in view the invention consists in a construction and combination of parts of which a preferred embodiment is illustrated in the accompanying drawings, wherein:

Figure 1 is a front elevational view of the invention.

Figure 2 is a top plan view with the arms positioned for use with a large sack.

Figure 3 is a view similar to Figure 2 with the arms positioned for use with a small sack.

Figure 4 is a sectional view on the plane indicated by the line 4—4 of Figure 2.

The invention comprises the reversible arms 10 pivotally mounted on a slide 11 which is pivotally adjustable on a standard 12, the latter upstanding from a base 14 to which it is secured by appropriate fasteners 15 extending through a foot 16 carried at the bottom of the standard.

The standard is preferably cross-sectionally angular as shown and the slide 11 is retained in its adjusted position with a thumb screw 17 threadingly engaged with a slide and bearing upon the standard.

The slide is formed with a forward extension 18 and spaced upstanding flanges 19 and 20, the one extending laterally beyond one side of the extension 18 and the other laterally beyond the other side. The flanges 19 and 20 are respectively formed with lips 21 and 22 having their upper faces in the plane of the extension 18, the lip 21 extending forwardly from the flange 20.

The arms 10 are pivotally mounted one on each flange, as indicated at 23 and on their outer surfaces are formed with double hooks 24, so that whichever end of the arms is dis-

posed upward, hooks may be provided for the attachment of sacks.

The pivotal connections of the arms are on opposite sides of the plane of the axis of the standard 12 and when disposed in one position bear upon the ribs 22 and 21 respectively, so that they have a spread adapted for the reception of a large sack which may be held with the mouth distended. This position of the arms is clearly illustrated in Figure 2. When the device is to be used for the small size sacks, the arms are swung over on their pivotal connections and then bear up on the upper face of the extension 18, overlapping at their pivoted ends, as indicated in Figure 2. The spread is thus reduced twice the spacing between the pivotal connections and they are positioned for the reception of a small sack.

The invention having been described what is claimed as new and useful is:

1. A sack holder comprising a supporting member, and arms pivotally mounted on said supporting member with their pivotal connections disposed on opposite sides of the plane of the center of said supporting member, the arms being swingable through 180° arcs to reverse their relative positions and reduce their normal spacing.

2. A sack holder comprising a supporting member, and arms pivotally mounted on said supporting member with their pivotal connections disposed on opposite sides of the plane of the center of said supporting member, the arms being swingable through 180° arcs to reverse their relative positions and reduce their normal spacing, the supporting member comprising a member with a forward extension and spaced upstanding flanges thereon, the flanges having lips lying in the plane of the extension and the pivotal connections with the arms lying in the flanges above the lips.

3. A sack holder comprising a supporting member, and arms pivotally mounted on said supporting member with their pivotal connections disposed on opposite sides of the plane of the center of said supporting member, the arms being swingable through 180° arcs to reverse their relative positions and reduce their normal spacing, the supporting

member comprising a member with a forward extension and spaced upstanding flanges thereon, the flanges having lips lying in the plane of the extension and the pivotal connections with the arms lying in the flanges 5 above the lips, the arms in one position resting upon the lips and in the other bearing on the upper face of said extension.

4. A sack holder comprising a supporting member, and arms pivotally mounted on said supporting member with their pivotal connections disposed on opposite sides of the plane of the center of said supporting member, the arms being swingable through 180° 10 arcs to reverse their relative positions and reduce their normal spacing, the supporting member comprising a standard and a slide 15 vertically adjustable thereon.

In testimony whereof he affixes his signature.

WILLIAM S. TOPPER.
